US00D538312S

(12) **United States Design Patent** (10) **Patent No.:** **US D538,312 S**
(45) **Date of Patent:** **** Mar. 13, 2007**

(54) **ABRASIVE ARTICLE WITH HOLES**

(75) Inventors: **Ehrich J. Braunschweig**, Woodbury, MN (US); **Edward J. Woo**, Woodbury, MN (US); **Charles J. Studiner, IV**, Cottage Grove, MN (US)

(73) Assignee: **3M Innovative Properties Company**, St. Paul, MN (US)

(**) Term: **14 Years**

(21) Appl. No.: **29/238,541**

(22) Filed: **Sep. 16, 2005**

(51) LOC (8) Cl. **15-09**

(52) U.S. Cl. **D15/126**; D8/70

(58) Field of Classification Search D8/62, D8/70; D15/124-126, 138, 139; 451/47, 451/56, 324, 443, 541, 544, 547, 548-551

See application file for complete search history.

Primary Examiner—Antoine D. Davis
Assistant Examiner—Patricia Palasik

(57) **CLAIM**

The ornamental design for an abrasive article with holes, as shown and described.

DESCRIPTION

FIG. 1 is a top perspective view of an abrasive article with holes, as shown;

FIG. 2 is a top view thereof;

FIG. 3 is a bottom view thereof; and,

FIG. 4 is a front side view thereof; the left, right, and back side views being identical thereto.
